(57) **CLAIM**

The ornamental design for a beverage cooler, as shown and described.

DESCRIPTION

FIG. 1 is a perspective view of a beverage cooler of our new design;

FIG. 2 is a front view of the beverage cooler of FIG. 1; FIG. 3 is a rear view of the beverage cooler of FIG. 1; FIG. 4 is a left side view of the beverage cooler of FIG. 1; FIG. 5 is a right side view of the beverage cooler of FIG. 1; FIG. 6 is a top view of the beverage cooler of FIG. 1; and, FIG. 7 is a bottom view of the beverage cooler of FIG. 1. The broken lines in the drawings depict portions of the beverage cooler that form no part of the claimed design.

1 Claim, 6 Drawing Sheets(56)
